Bata, narodni podnik, Zlin, CzechoslovakiaApplication March 19, 1948, Serial No. 15,753
In Czechoslovakia March 27, 1947

3 Claims. (Cl. 28—71.5)

1

This invention relates to a simple and effective device for guidance of spun fibres during their drawing off.

It is usual to lead a bundle or group of spun fibres, obtained for example by the dry spinning of polyamides or the like, to a take-up roller, and to wind them upon it in a number of helical windings, whereafter the bundle of fibres is wound upon a reel or bobbin, being simultaneously stretched if so desired. For high spinning speeds, it is very important to provide easy guidance of the bundle of fibres upon the take-up roller continually.

The object of the invention is to provide a fibre-spacing holder and means for winding the ingoing fibres around both the take up roller and the holder so that they are formed in properly spaced helical windings. In this manner the required windings are formed, their number being sufficient to prevent the fibres from sliding in the direction of the pull, when being drawn off.

The invention is illustrated, by way of example, in the accompanying drawing, which is an elevation, partly in section, of a take up roller and associated parts.

The device according to the invention consists of a take up roller 1 journalled on a stationary supported bearing or journal member the bottom of which is indicated by 4. The roller 1 is continuously rotated on the member 4 by a belt-driven pulley 8 which is firmly connected with the take up roller 1. The member 4 is extended above the take up roller 1 as a screw 4'. The axis of this screw is identical with the axis of rotation of the take up roller 1. A stationary fibre-spacing holder 2 parallel with the axis of the take up roller is secured to the member 4, being formed with grooves for locating the fibres. Through the stationary hollow member 4 extends a turnable shaft 7 which can be turned by means of a wheel 6 secured to its lower end, the shaft 7 being also axially slidable through the journal member 4. The upper end of the shaft 7 is extended as a finger 9 with a terminal eye 9'. Through this eye 9' passes a fibre-guiding arm 3 with a terminal eyelet 3', through which the ingoing fibre or bundle of fibres is drawn. The guiding arm 3 is integral with a boss 5 made as a nut which engages the screw 4'.

When the fibres are drawn off from the usual spinneret (not shown) in the direction of the arrow to any usual reel or bobbin (not shown) it is possible to form them into a sufficient number of windings on the take up roller to prevent

2

the fibres from sliding in the direction of the pull. This is performed, after the fibres have been passed through the eyelet 3', by turning the wheel 6 in the opposite direction to that of the take up roller as many revolutions as the number of windings considered necessary to prevent the fibres from sliding in the direction of the pull. When the wheel 6 is turned, the finger 9 carries the guiding arm 3 around both the rotating take up roller and the stationary holder 2, the shaft 7 simultaneously sliding upwards. The eyelet 3' thus follows the helical path of the thread of the screw 4, so that the fibres are helically wound upon the take up roller 1 and the holder 2, which holds them properly spaced apart.

When a satisfactory frictional drag is applied to the fibres by the ultimately selected number of windings around the take up roller and the holder, turning of the wheel 6 is stopped. Thereafter, the drawing off operation is carried on, the take up roller 1 revolving as usual.

In the example, the screw 4 is co-axial with the take up roller 1 but it is sufficient if they have parallel axes. Instead of the screw device shown, the arm 3 could be made as a pivotal member and arrangements could be made to lift the arm manually about its pivot as the arm rotates; the same effect could be obtained by making the arm of the guide of flexible material and by manually lifting it during the rotary movement.

An advantage of the arrangement according to the invention consists in the very easy and very quick manner of guidance of the bundle of fibres upon the take up roller, thus allowing the operation even at high velocities of drawing off.

I claim:

1. A device for guidance of spun fibres during their drawing-off, such device comprising a support, a rotary take-up roller, means for continuously rotating said roller borne by said support about its axis, a stationary fibre-spacing holder extending from said support parallel to said axis, and a fibre guide which is connected to said support is movable not only around said roller and holder but also axially thereof so as to wind the fibres helically thereon.

2. A device for guidance of spun fibres during their drawing-off, such device comprising a rotary take-up roller, means for continuously rotating said roller about its axis, a stationary fibre-spacing holder extending alongside said roller, a fibre guide which is movable rotatably around said roller and holder, a stationary screw

extending lengthwise of said roller and holder, and a nut on said guide engaging said screw so that if said guide is moved rotatably said screw will displace the guide axially in order to wind the fibres helically thereon.

3. A device for guidance of spun fibres during their drawing-off, such device comprising a stationary hollow journal member, a rotary take-up roller, journaled on said member, means for continuously rotating said roller on said member, a stationary fibre-spacing holder secured to said member and extending parallel thereto, a screwed extension on said member, a nut on said extension, a fibre guide extending from said nut and having an eyelet through which fibres 10 15 going to the roller are led, and rotatable means extending through said journal member and en-

gaging said fibre guide so that rotation of said rotatable means effects helical movement of said nut on said screwed extension and corresponding helical movement of said eyelet and winding of ingoing fibres around both said roller and holder.
